GARMENT HANGER STRUCTURE

Philip G. Sage, 240 Central Park South, New York, N.Y.

Filed May 25, 1959, Ser. No. 815,462

4 Claims. (Cl. 223—94)

This invention relates to garment support structures and more particularly to a combination structure facilitating packaging and suspension of garments.

It is one of the primary objects of the invention to provide means affording the adjustment of the garment support or hanger to the respective size, especially to the width of the shoulders of a garment to be suspended therefrom.

It is another object of the invention to provide means ensuring easy application of a garment, in particular of a jacket, to a garment hanger of the aforesaid type, which is constructed in a manner as to permit ready draping of the garment thereon, thereby aiding in packaging and shipping of the latter without being subjected to crushing or wrinkles.

Yet another object of the present invention is to provide means contributing to a very simple, inexpensive garment support structure, which can be mass produced from cardboard, pasteboard, plastic and like materials, is sturdy, not bulky and may be collapsed when not in use.

Still a further object of the invention is to provide means envisioning improved and complete shoulder support for garments of various sizes and simultaneously a holding fit for engaging the back and front of garment parts in suspended condition.

A further object of the invention is the provision of means contributing to an easily manipulatable garment hanger structure, which may be adjusted and shaped so that different desirable positions may be attained according to garment shoulder size and for draping the respective garment, and which permits the insertion of the cuffs of trousers and carrying of the hanger loaded with garment parts, whereby the latter are securely retained in position on said novel hanger structure.

These and other objects of the invention will become further apparent from the following detailed description, reference being made to the accompanying drawing showing a preferred embodiment of the invention.

In the drawing:

Fig. 1 is a front elevational view of an extensible garment support embodying the invention, parts being shown in various positions, indicated in broken lines;

Fig. 2 is a fragmentary and enlarged view of the support of Fig. 1, seen partly in section and broken away for the sake of clarity;

Fig. 3 is a section taken along lines 3—3 of Fig. 2;

Fig. 4 is a section taken along lines 4—4 of Fig. 2;

Fig. 5 is a diagrammatic view of a detail referred to in the specification; and

Fig. 6 is an elevational view of an extension element.

Referring now more particularly to the drawing, there is disclosed a garment hanger support 10 having a main board-shaped member 11 and two garment shoulder holder or extension elements 12, 13, which are arranged for relative movement and adjustment with respect to each other and to member 11.

2

Member 11 is defined by an upper curved end edge 14 from which extend substantially straight downward edges 15 and 16. In the upper portion 17 of member 11 there is provided an opening 18 to facilitate grasping of the board member 11 for carrying same and further a lengthy slot 20 having a median straight portion 21 and further opposite serrated slotted end portions 22 and 23.

At the uppermost end of board member 11 and centrally thereof there is provided a reinforcement 24 for anchoring a hook member 25 from which the garment support may be suspended.

The serrated means or end portions 22 and 23 of slot 20 are arranged to facilitate movement and adjustment of shoulder holder or extension elements 12, 13 about 15 to be described. To this end, each shoulder extension means, such as 13, is provided with an opening 13a through which extends a screw bolt 26 having a head 27, a square-shaped bolt section and a threaded end section 29 with which a knurled thumb nut 30 is engaged, whereby by each of the shoulder holder elements 12 and 13 may be rotatably and displaceably affixed in position relative to garment shoulder member 11 in a manner as clearly seen in Fig. 2.

Shoulder extension element 13, as shown in dot and 25 dash lines, may be outwardly moved from the full line position of Fig. 1 for being swivelled and thereafter clamped or tightened in a desired position at 13c relative to main member 11 as indicated in full lines in Fig. 2, so that the upper rounded edge 13b conforms to the outline 30 of upper rounded edge 14 of main member 11.

It will be noted that the serrated end portions 22 and 23 have a series of upwardly extending teeth or projections 31 between which gaps 32 are provided. The square-shaped bolt 28 of adjustment bolt arrangement 26 may 35 be either located, as seen in Fig. 5 on the top of one of the projections or lowered for being seated in a gap 32, as it is well understood, in order to define the desired position of shoulder holder or extension element 13.

It will be noted that each of the shoulder holder elements or means 12 and 13 may also be rotated or swung about square-shaped bolt 28 by means of opening 13a (Fig. 4) and then clamped or tightened by thumb screw 30 in such position, whereby, for example, rounded edge 13b forms a prolongation of corresponding curved 45 edge 14.

It is well understood that what has been set forth with respect to shoulder support extension or element 13 is equally applicable to element 12, so that further explanations in that respect may be omitted.

50 Thus, garment hanger 10 may be readily adjusted to various widths of shoulders of garments, in particular of jackets, while the trousers of such garment may be threaded through median slot portion 21 for support thereby.

55 It is well understood that other clamping or attaching means 26 may be employed in connection with this invention and further that the shoulder extension portions may be not flat but rather bent at their outer contour line at 13b so as to be approximately aligned with curved upper end edge 14. In such case, the garment hanger structure may be made of a plastic or similar material.

60 It is further understood that slot 18 not only may be used to grasp the main body 11 of the garment hanger structure for carrying purposes but may also be employed for holding other garment parts such as undershirts, neckties and the like.

65 The downward extension of main body 11 may be commensurate with the length of the jacket to be suspended from hanger structure 10 or for facilitating packaging of 70 a jacket together with the trousers, neckties, etc. in a carton or piece of luggage.

In the case of packaging the garment, hook 25 may be

withdrawn from reinforcement 24 in order to facilitate location of the garment hanger structure in a carton or like container.

It can thus be seen that there has been provided in accordance with the invention a garment hanger structure comprising a substantially flat supporting main body bounded by a curved upper end edge and lateral edges extending in downward direction from said curved upper end edge, said main body being provided with a transverse slot disposed a distance below said curved upper end edge, said slot including a straight median section and lateral opposite serrated slot end sections, two oppositely arranged shoulder extension portions connected to said end slot sections and in superposed position to said main body, and respective means passing through said end slot sections and through respective openings provided in said extension portions for attaching the latter to said main body and in such manner that said extension portions may be swivelly moved about said attaching means relative to said curved upper end edge and along said slot outwardly beyond said curved upper end edge of said main body, said attaching means being adapted to retain said extension portions in predetermined selected positions on said main body, each of said extension portions being defined by curved end edges shaped for complementary alignment with said curved upper end edge of said main body, thereby to extend the support of the shoulders of a jacket, when placed on the curved upper edge of said main body, beyond said lateral edges of said main body and onto the respective curved end edges of said extension portions commensurate with the width of the shoulders of said jacket, said median slot being adapted to receive portions of the trousers of a garment.

Referring again to lengthy slot portion 21 of Fig. 1, there is arranged at 21a a lower and narrower further slot which may be employed for threading through the cuffs of a pair of pants inserted in median slot 21 so that the pants or trousers will be prevented from sliding out of slot 21.

It is further to be mentioned that serrated slotted end portions 22 and 23 may be provided with gradations (not shown) in accordance with the standard measurements of garments or widths of jackets to be placed on the novel garment support 10.

A marked advantage of the garment hanger structure resides further in the fact that it is extremely light in weight, takes up a comparatively small space, and may be relatively short in length but sufficient to serve as a display and draping support whether the same is used for suspension from a hook in a closet or is placed in a carton for shipment, so that the jacket or other garment part conforms to the adjusted garment support structure and remains free from wrinkles and other undesirable effects heretofore observed in known garment structures.

Various changes and modifications may be made without departing from the spirit and scope of the present invention and it is intended that such obvious changes and modifications be embraced by the annexed claims.

Having thus described the invention, what is claimed as new and desired to be secured by Letters Patent is:

1. A garment support and draping device comprising a body of substantially flat material provided with at least two spaced apart elongated slots, one of said slots extending in horizontal direction and having a median portion and opposite end portions, said end portions each being provided with serrated means, a curved end edge forming the upper boundary of said body, and shoulder extension means rotatably and displaceably received in each end portion of said one elongated slot, said shoulder extension means being provided with clamp means engage-

able with said body and with said serrated means for clamping said extension means in position relative to said curved end edge of said body, each of said shoulder extension means being defined by an arcuate upper end edge positionable for substantial alignment with the curved end edge of said body to thereby provide lateral extensions relative to the body and to conform said support to predetermined shoulder width of a garment and to drape the latter over said body and said lateral extensions, the other slot being adapted to engage at least a part of a pair of trousers when said trousers are inserted into the median portion of said one slot.

2. A device according to claim 1, said serrated slot end portions including substantially rectangular projections and rectangular-shaped gaps between adjacent projections, said clamp means including a retainer head, a threaded bolt portion and a square-shaped bolt portion located between said head and said threaded bolt portion,

15 15 said square-shaped bolt portion being adapted to engage the top of one of said projections and with one of the gaps, respectively, said threaded bolt portion being engaged by a thumb screw, each of said shoulder extension means being provided with an opening sufficient to pivotally move said extension means relative to said clamp means, said thumb screw being adapted to firmly press said extension means against said body in respective positions of said clamp means in said serrated end slot portions.

20 20 30 30 3. A device according to claim 1, said body being provided with a further slot located between said curved upper end edge and said one slot, said further slot being adapted to facilitate insertion of the hand of an operator for grasping and carrying said body.

25 25 35 35 4. A garment hanger structure comprising a body of substantially flat material terminating in an upwardly curved upper end edge, said body being provided with at least one horizontal, elongated slot disposed a distance below said upper end edge, said one slot having a straight median portion and two opposite lateral serrated end portions, said serrated end portions including projections and a gap located between two adjacent projections, two oppositely arranged shoulder extension means having openings and connected with said serrated end portions, and respective clamp means passing through said serrated
